DOOR PULL

Lewis L. Kadleck, Dallas, Tex.

Application August 17, 1949, Serial No. 4,545

Term of patent 3½ years

(Cl. D10—8)

To all whom it may concern:

Be it known that I, Lewis L. Kadleck, a citizen of the United States of America, residing at Dallas, in the county of Dallas and State of Texas, have invented a new, original, and ornamental Design for Door Pull, of which the following is a specification, reference being had to the accompanying drawing, forming part thereof.

In the drawing

Fig. 1 is a perspective view of a door pull, showing my new design;

Fig. 2 is a top plan view of the door pull;

Figure 3 is a side elevational view of the door pull;

Figure 4 is a bottom plan view of the door pull;

Figure 5 is a front end view of the door pull.

I claim:

The ornamental design for a door pull, as shown.

LEWIS L. KADLECK.
